(57) **CLAIM**

The ornamental design for an electronic display board, as shown and described.

DESCRIPTION

FIG. 1 is a perspective view of an electronic display board showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a perspective view of the “electronic display board”, which is in another state of use.

The broken lines in the drawings are employed to show environmental structures only, and form no part of the claimed design.
